(57) **CLAIM**

The ornamental design for golf bag as shown and described.

DESCRIPTION

FIG. 1 is a first perspective view of the golf bag showing my new design;

FIG. 2 is a first side view of the golf bag, thereof;

FIG. 3 is a front view of the golf bag, thereof;

FIG. 4 is a second side view of the golf bag, thereof;

FIG. 5 is a rear view of the golf bag, thereof;

FIG. 6 is a top view of the golf bag side, thereof; and,

FIG. 7 is a bottom view of the golf bag, thereof.

In FIGS. 1-7, the lighter broken lines showing portions of the golf bag are for purposes of illustrating environment and form no part of the claimed design. The heavier dashed lines shown in the views of the golf bag side pockets and hip pad are representative of stitching that forms part of the claimed design.
